UNITED STATES PATENT OFFICE.

SIGMUND L. LEDERER, OF PROVIDENCE, RHODE ISLAND.

DESIGN FOR A WATCH BRACELET.

Application filed January 13, 1925. Serial No. 12,043. Term of patent 7 years.

To all whom it may concern:

Be it known that I, SIGMUND L. LEDERER, a citizen of the United States of America, residing at Providence, county of Providence, State of Rhode Island, have invented a new, original, and ornamental Design for a Watch Bracelet, of which the following is a specification, reference being had to the accompanying drawing, forming a part thereof.

I claim:

The ornamental design for a watch bracelet, as shown.

SIGMUND L. LEDERER.
